UNITED STATES PATENT OFFICE.

CHARLES H. GAFFNER AND ELMER L. JONES, OF SEATTLE, WASHINGTON.

DOOR FOR MULTIPLE MAIL RECEPTACLES.

Application filed July 13, 1925. Serial No. 43,127.

This invention relates to multiple mail receptacles for apartment houses or the like and, more especially, to the receptacle doors.

The object of our invention is the provision 5 of strong, efficient and conveniently regulated means whereby all of the mail receptacles of a group thereof are readily accessible to the carrier for distributing mail therein, and the individual receptacles accessible 10 only to persons entitled to receive their mail in the respective receptacles.

The invention consists in the novel construction, adaptation and combination of parts hereinafter described and claimed.

15 In the accompanying drawing,—

Figure 1 is a front elevation, with parts broken away, of a group of mail receptacles to which is applied door devices embodying our invention; Fig. 2 is a detail sectional 20 view on line 2—2 of Fig. 1; and Fig. 3 is a rear elevation of the frame of the master door illustrated in Figs. 1 and 2 with one of the supplementary doors and its frame in place. Fig. 4 is a vertical transverse section 25 of the wall of a building showing a modified construction of receptacles and door devices; and Fig. 5 is a fragmentary front elevation of Fig. 4.

Referring to Figs. 1, 2 and 3, the 30 numeral 10 represents a cabinet intended for use in the wall of a building, said cabinet being divided by partitions 11 into vertical spaces which, in turn, are divided by horizontal partitions 12 into compartments, such 35 as 13.

For the open front of said cabinet is provided a door 14, hereinafter designated as the master door, which may be connected at one side by means of hinges 15 to said cabinet or, as shown in Fig. 1, to a casing 16 which is rigid with the cabinet.

In the opposite side of the door from said hinges it is provided with a lock 17 whose bolt 18 is engageable in a keeper (not shown) 45 which is provided within said casing.

The key for this lock is intended to be in the possession of the postman or carrier, permitting him to open the master door for distributing mail matter among the various 50 compartments or boxes of the cabinet. Said master door is constructed of a rigid rectangular frame having side rails 19, 20, and top and bottom rails 21 and 22.

Said rails are desirably of angle bars to 55 afford flanges 23 which are disposed in the plane of the front of the door. In practice

said door frame is preferably of steel, against the exposed surfaces of which is a cover plate 24 of brass, bronze, or the like.

Provided within the door frame and rigid therewith is a plurality of vertically disposed bars 25 dividing the frame opening into spaces 26 (Fig. 3) which are disposed to be in front of the respective vertical rows of compartments 13 when the door is in its closed position. Disposed one above the other in each of the frame spaces 26 is a series of supplementary frames 27, one being shown in Fig. 3, having openings, as 28 Fig. 2, which communicate with the respective compartments 13.

For each of these openings is provided a door 29, hereinafter designated as box-door, connected at one side by hinges 30 to the associated frame 27 and provided with a lock indicated by 31 whose bolt 32 is adapted to engage within an aperture in the adjacent side rib element 35 of the respective frame 27.

The keys for the locks of the box-doors 30 are furnished to persons receiving mail matter therein. As illustrated, the supplementary frames 27 are formed to provide a facing 33 to juxtapose against the front surface of the master-door frame bars 25. The rib 35 elements 35 extend into the spaces 26 of the master door to receive bolts or rivets 36 engaging in holes provided in the respective bars 25 of the frame of the master door.

In Figs. 4 and 5, is illustrated an embodiment of the invention applicable for use with a cabinet 10¹ included within a relatively thin partition wall W of a building. Under such a condition the compartments 13¹ are arranged to have their maximum 95 lengths, as shown in Fig. 4, disposed vertically. The compartments are disposed preferably in a group comprising two horizontal rows one above the other separated by a partition 12¹.

100 The openings through which access is had by the user into the compartments are disposed adjacent to said partition.

The master door 14¹ for the assembly of compartments now being considered is provided with a rigid frame having side rails 19¹, 20¹, a top rail 21¹ and a bottom rail 22¹, of angle bars, preferably. Such door frame is also advantageously reinforced by means of a horizontal rail 40 preferably of channel 110 bar structure. This master door, like that hereinbefore described, is hung on hinges 15¹.

and is provided with a lock which is indicated by 17¹ whose bolt engages in a suitable socket provided in the casing 16¹. The master door 14¹, like the aforesaid master door 14, has mounted therein supplementary frames 27¹ for the box-doors 29¹. Each of the latter being hung on hinges 30¹ whose key is carried by the person using the respective compartment.

10. The operation of the invention is as follows: The postman with his key unlocks the master door to open the same for distributing mail into the proper compartments. After the master door is closed and locked, 15 the persons whose mail is contained in the various compartments may with their keys open the box-doors pertaining only to their respective compartments. By such devices—the master door and box-doors—un-

authorized persons are prevented from gaining access to mail not belonging to them. 20

What we claim, is,—

In combination, a master door comprising a main frame having a rectangular opening therein, series of smaller frames disposed 25 one above the other in said opening, spacing bars rigid with said main frame, the smaller frames of each of said series being held in spaced relation with those of the other series, means for securing the smaller frames to the main frame through the medium of said spacing bars, and doors for the openings of the smaller frames hinged connected to the last named frames. 30

Signed at Seattle, Washington, this 10th 35
day of June, 1925.

CHARLES H. GAFFNER.
ELMER L. JONES.
